Edgar Gate, ATTORNEYS.

UNITED STATES PATENT OFFICE.

WALTER W. HALL, OF BROOKLYN, NEW YORK, ASSIGNOR OF ONE-HALF TO JOSEPH BOUM, OF BROOKLYN, NEW YORK.

GAME APPARATUS.

1,102,501.

Specification of Letters Patent.

Patented July 7, 1914.

Application filed August 2, 1913. Serial No. 732,557.

To all whom it may concern:

Be it known that I, WALTER W. HALL, a citizen of the United States, and residing at Brooklyn, in the county of Kings and State of New York, have invented certain new and useful Improvements in Game Apparatus, of which the following is a specification, such as will enable those skilled in the art to which it appertains to make and use the same.

This invention relates particularly to what are known as games of bowling, commonly called ten pins, and which involve an alley-way and pins adapted to be placed thereon; and the object of the invention is to provide improved means whereby the exact placing of the pins on the alley-way, or the exact "spotting" of the pins in the desired position will be assured, and where- 20 by the placing of the pins in a vertical position on the alley-way will be impossi- 25 ble, except when said pins are placed in their proper or exact position, thus doing away with the annoyance and dissatisfaction caused by careless or incompetent pin 30 setters, or pin boys, failing to place the pins on their allotted places, or in their proper positions.

The invention is fully disclosed in the following specification of which the accompanying drawing forms a part, in which the separate parts of my improvement are designated by suitable reference characters in each of the views, and in which:—

35 Figure 1 is a sectional view of a pin and a part of an alley-way and showing my improvement; Fig. 2 a view similar to Fig. 1, but showing a modification; Fig. 3 a view similar to Fig. 1, but on an enlarged 40 scale, and showing the pin partly raised, and; Fig. 4 a view similar to Fig. 1 but on an enlarged scale and showing the pin in a different position.

In the drawing forming part of this specification, I have shown at *a* an ordinary bowling pin and at *b* a part of an alley-way, and in the practice of my invention, as shown in Fig. 1, I form in the alley-way, a chamber *e* which is covered by 45 a plate *f* countersunk in the alley-way and held in place by screws *f*², or in any desired manner, and the plate *f* is provided with a central aperture *f*³ adapted to re-

ceive a part of a ball *c* supported on a spring *d* secured in the bottom of the chamber *e*.
55

Countersunk in the bottom of the pin *a* is a recessed plate *g* having a central recess *g*² which is arc-shaped in cross section and the depth of which is approximately 60 one-third of the diameter of the ball *c*, or less, and the curve of the arc on which the said recess is formed is the same as the curve of the circumference of the ball *c*, and said ball closely fits in said recess when 65 the pin is in position.

The spring *d* on which the ball *c* is placed is preferably a spiral spring and the smaller end of said spring is provided with a shank *d*² which passes into the bottom of the 70 chamber *e* and by which said spring is held in place, and the ball *c* is normally pressed by said spring against the bottom of the apertured plate *f*, and approximately 75 one-third of the ball, or less, fits in the aperture *f*³, and part of said ball passes through said aperture and fits in the recess *g*² in the plate *g*. The chamber of the ball and the transverse dimensions and the depth of the chamber *e* and the form and 80 dimensions of said spring are such as to permit of the free vertical and free lateral movement of said ball *c* in said chamber a distance approximately equal to one-third of the diameter of the ball, or over, and 85 the walls of the central aperture in the apertured plate *f*² are beveled to correspond with the curve of the arc on which the recess in the plate *g* is formed. With this construction the ball *c* may be depressed 90 from a third to a half of its diameter, or more, and if the pin *a* be moved laterally, with the construction shown in Fig. 1, the ball *c* will be depressed into the chamber *e*, as the pin passes therethrough, but will 95 immediately assume its normal position, as shown in Fig. 1, and the pin may be placed in position, as will be readily understood, and the ball *c* will serve as a means for insuring that said pin be placed in its 100 proper or exact position.

In the construction shown in Fig. 2, the chamber *e* is formed in the pin *a*, the plate *f* connected with the bottom of said pin and the spring and ball *d* and *c* placed in said 105 chamber, while the recessed plate *g* is placed

in the alley-way *b*, and with this construction the operation will be the same, the ball *c* serving as a means for insuring the proper placing of the pin, and if the pin be struck by a bowling ball, the operation of the ball *c* will be the same as that hereinbefore described. The correct operation of this construction depends entirely upon the size or dimensions of the chamber *e*, and the method 10 of supporting the ball in said chamber, and in the fact that the aperture in the plate *f* is formed centrally therein and is also of much less transverse dimensions than said chamber *e*, this construction permits the ball 15 *c* to be entirely depressed in the chamber *e*, and also permits of the free lateral movement of said ball in said chamber, which lateral movement is necessary in placing a game of ten pins involving the use of pins 20 and an alley way.

In Fig. 4, I have shown the position the ball *c* assumes when the pin *a* is moved laterally, and it will be understood that when the pin *a* is struck by a bowling ball, unless 25 said pin is lifted off the alley-way, the ball *c* will assume a position in the chamber *e* similar to that shown in Fig. 4.

I am aware that apparatus of this class involving a construction somewhat similar 30 to mine, have heretofore been employed, but in all apparatus of this class, heretofore used, the chamber *e* has been so small that it would not permit of the lateral and vertical movement of the ball *c*, as herein shown 35 and described, and this free lateral movement of said ball must be provided for in order that it will be free to move in any direction when the pin *a* is struck by a bowling ball.

40 My invention is not limited to a spiral spring *d*, and other forms of spring may be employed, but with this exception the construction employed must be similar to that herein shown and described, or such as to 45 permit the ball *c* to move freely and easily in a vertical and lateral direction within the chamber *e*, whether said chamber be

formed in the alley-way, or in the pin, as shown in Figs. 1 and 2.

My invention is also not limited to the 50 game of ten pins, but may be employed in any game employing bowling pins and an alley-way.

Having fully described my invention what I claim as new and desire to secure 55 by Letters Patent is:—

A game apparatus involving an alley-way and a bowling pin or pins, said alley-way and pin or pins being provided, one with a countersunk recessed plate and the 60 other with a chamber closed by a centrally apertured and countersunk plate, a spring placed in the bottom of said chamber and a ball placed on said spring and normally 65 pressed thereby against said apertured plate, the recess in the recessed plate being arc-shaped in cross section and the depth thereof being approximately one-third, or less, of the diameter of said ball, the curve 70 of the arc on which said recess is formed being the same as the curve of the circumference of said ball, and the aperture in the apertured plate being of such dimensions as to receive approximately one-third 75 of said ball, the diameter of the ball and the transverse dimensions and the depth of said chamber and the form and dimensions of said spring being such as to permit of the free vertical and lateral movement of 80 said ball in said chamber a distance approximately equal to one-third of the diameter of the ball, or over, and the walls of the central aperture in the apertured plate being also beveled or curved to correspond 85 with the curve of the arc on which the recess in the recessed plate is formed.

In testimony that I claim the foregoing as my invention I have signed my name in presence of the subscribing witnesses this 31st day of July 1913.

WALTER W. HALL.
